UNITED STATES PATENT OFFICE.

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY.

LOOPER-ACTUATING MECHANISMS FOR SEWING MACHINES.

Application filed August 5, 1922. Serial No. 579,806.

This invention relates to looper-actuating mechanisms for sewing machines and has for an object to provide such a mechanism which is easy of construction, compact, durable, efficient in operation, and in which the necessary adjustments are provided to adapt it to various classes of work and stitching operations.

In accordance with the present invention one or more loopers are secured upon a suitable looper-carrier and are given loop-taking movements in the direction of their length across the line of seam-formation and sidewise, or so-called needle-avoiding movements, in the direction of the line of seam-formation.

The looper-carrier is preferably adjustably secured upon a tubular member which in turn is rotatably mounted upon a sleeve 20 slidably supported upon an arbor fixed in bearings in the machine base.

The looper-carrier is given its loop-seizing movements by an eccentric secured upon a main or actuating shaft extending lengthwise of the machine base, which eccentric is operatively connected by a suitable pitman to an arm projecting from said tubular member. Sidewise movements are imparted to the looper-carrier from the second eccentric also secured upon the main-shaft and which is surrounded by a strap having a depending pin which slidably fits within a socket formed in said sleeve.

The invention is illustrated in its preferred form in the accompanying drawings in which Fig. 1 is a side elevation, partly in section, of a portion of a sewing machine embodying the present invention; Fig. 2 is a plan view thereof; Fig. 3 is a sectional view taken on the line 3—3, Fig. 1; Fig. 4 is a similar view taken on the line 4—4, Fig. 1, and Fig. 5 is a detail sectional view of parts employed for supporting the looper-carrier.

Referring more particularly to the drawings the invention is shown embodied in a sewing machine comprising a base 1, head 2, feeding mechanism 3, cloth-presser 4 and a needle-bar 5 which latter carries one or more needles 6. Journaled in bearings 7 rising from the base 1, is a main or actuating shaft 8 which is rotated in a manner common to sewing machines.

The improved looper mechanism com-

prises one or more loopers 9 secured upon a looper-carrier 10 provided with a split hub 11 adapted to be adjustably clamped, by means of screws 12, upon a tubular looper-actuating member 13 provided with an arm 14 which carries a ball 15 provided with a steady-pin 16. The tubular member 13 is rotatably mounted upon a tubular shaft or sleeve 17 having a reduced portion 17' affording a shoulder 18. The reduced portion 17' of the sleeve 17 is preferably threaded at 20 and a split collar 19 is threaded thereon, thus the shoulder 18 and the collar 19 afford means for preventing endwise movement of the member 13 on the sleeve 17. A split pinch-collar 21 preferably fits over the collar 19 and holds it in any position of adjustment on the sleeve 17, which is slidably supported upon a rod or arbor 22 fixed in the base 1, transversely of the main-shaft 8, by means of the set-screws 23.

Oscillatory movements are imparted to the tubular member 13 and the attached looper-carrier 10 by an eccentric 24 secured upon the shaft 8. A pitman 25 is formed at its upper end with a strap 26 which surrounds the eccentric 24 and at its lower end with a strap 27 which receives the ball 15. To the pitman 25 there is secured a slotted guide-block 28 which coacts with the pin 16 to steady the pitman and prevent it from wobbling on the eccentric 24.

Thus through the connections pointed out the looper-carrier is rocked from the main-shaft and the looper or loopers carried thereby are given movements in the direction of their length across the line of seam-formation and cooperate with the needle or needles in the formation of stitches.

Sidewise or needle-avoiding movements are imparted to the looper from an eccentric 29 secured upon the shaft 8. A strap 30 surrounds the eccentric 29 and is provided with a pin 31 which is slidably fitted within a tubular socket 32 carried by the sleeve 17 mounted for sidewise movement upon the arbor 22.

Both looper-actuating elements on the main-shaft are disposed closely adjacent between main-shaft bearings, which contributes to compactness and short operative connections involving a minimum of inertia and momentum, and hence vibration of the machine under high speed conditions.

From the foregoing description it will be observed that the present looper-operating mechanism possesses advantages in manufacture, is efficient in operation, and provides for the ready adjustment of the loopers both lengthwise and sidewise by merely loosening the clamp-screws 12 and moving the looper-carrier axially about or lengthwise of the tubular member 13.

Having thus set forth the nature of the invention, what I claim herein is:

1. A looper-actuating mechanism for sewing machines comprising a main-shaft, an eccentric thereon, an arbor, a sleeve slidingly mounted upon said arbor, a tubular member supported upon said sleeve, a looper-carrier secured upon said tubular member, a looper secured upon said looper-carrier, a connection between said tubular member and said eccentric for imparting lengthwise movements to said looper, a second eccentric on said main-shaft, and means connecting said second eccentric with said sleeve for imparting sidewise movements to said looper.

2. A looper-actuating mechanism for sewing machines comprising a main-shaft, an eccentric thereon, an arbor, a sleeve slidingly fitted on said arbor, a tubular member rotatably secured upon said sleeve and provided with an arm, a looper-carrier adjustably secured upon said tubular member, a pitman connecting said eccentric with said arm for imparting lengthwise movements to said looper, a second eccentric fixed upon said main-shaft, a strap surrounding said second eccentric, and a pin-and-socket connection between said eccentric strap and said sleeve for sliding said sleeve on said arbor and giving sidewise movements to said looper.

3. A looper-actuating mechanism for sewing machines provided with a base, a main-shaft supported thereby, an actuating element secured upon said main-shaft, an arbor supported transversely of said main-shaft, a looper-carrier supported upon said arbor and provided with a looper, means intermediate said actuating element and said looper-carrier for imparting oscillatory movements to said looper-carrier in the direction of the length of the looper, a second actuating element carried by said main-shaft, and a sliding connection between said second actuating element and the looper-carrier for giving sidewise movements to said looper.

4. A looper-actuating mechanism for sewing machines including a main-shaft, an eccentric thereon, an arbor extending transversely of said main-shaft, a sleeve slidingly mounted upon said arbor, a tubular member rotatably supported upon said sleeve and provided with an arm, a looper-carrier secured upon said tubular member, a looper carried thereby, a pitman connecting said eccentric with said arm for imparting lengthwise movements to said looper, and means for imparting sidewise movements to said looper.

5. A looper-actuating mechanism for sewing machines including a main-shaft, an eccentric thereon, a strap surrounding said eccentric, an arbor transverse to said main-shaft, a sleeve slidably mounted upon said arbor, a tubular member secured upon said sleeve and partaking of the movements thereof, a looper-carrier secured upon said tubular member, a looper secured upon said carrier, a pin-and-socket connection intermediate said eccentric and said sleeve for imparting sidewise movements to said looper, and means for imparting lengthwise movements to said looper.

6. A looper-actuating mechanism for sewing machines including a main-shaft, an arbor sustained transversely of said main-shaft, a sleeve slidably mounted upon said arbor, one portion of said sleeve being reduced to afford a shoulder, a tubular member rotatably mounted upon said reduced portion, a collar secured upon said reduced portion and cooperating with said shoulder to confine said tubular member in position endwise on said sleeve, a looper-carrier mounted upon said tubular member, a looper secured to said looper-carrier, and means for giving to the looper both lengthwise and sidewise movements from said main-shaft.

7. A looper-actuating mechanism for sewing machines including a base, a main-shaft, an arbor sustained by said base, a sleeve slidably mounted upon said arbor, a tubular member mounted upon said sleeve coaxially with the latter and held against endwise movement relative thereto, said tubular member being adapted to turn relative to said sleeve, a looper-carrier supported upon said tubular member, a looper secured upon said looper-carrier, means for effecting both axial and lengthwise adjustments of said looper-carrier on said tubular member, and means for actuating said looper-carrier.

8. A looper-actuating mechanism for sewing machines including a base, a main-shaft, an arbor sustained by said base, a sleeve slidably mounted on said arbor, a tubular member mounted on said sleeve coaxially with the latter and held against endwise movement relative thereto, said tubular member being adapted to turn relative to said sleeve, a looper-carrier, adjustable means for securing said looper-carrier upon said tubular member, said means being constructed and arranged to permit of either axial or lengthwise adjustment of the looper-carrier on said tubular member whereby the looper may be given either lengthwise or sidewise adjustment, and means for actuating said looper-carrier.

9. A looper-actuating mechanism for sewing machines comprising in combination with the frame-bearings and the main-shaft journaled therein, a support mounted to slide transversely of the main-shaft, a rocking looper-carrier mounted thereon, a plurality of actuating eccentrics mounted upon said shaft on opposite sides of the vertical plane of the axis of rocking movement of the looper-support, and operative connections between said actuating eccentrics and said support and looper-carrier, respectively, whereby they are given their respective movements.
- 10 15 10. A looper-actuating mechanism for sewing machines comprising a main-shaft, a looper, a looper-carrier mounted to rock and slide on an axis extending below and transversely of said main-shaft, an eccentric on said main-shaft, a pin-and-socket

sliding connection transverse to both said main-shaft and axis between said eccentric and said looper-carrier for imparting to the latter its sliding movements, a second eccentric on said shaft, and a pitman connecting said eccentric to said looper-carrier for rocking the latter. 25

11. In a sewing machine, a frame, an arbor fixed therein, an endwise movable sleeve fitted upon said arbor, a looper-carrier mounted for rocking movements upon and relative to said sleeve coaxially with the latter and confined against endwise movement relative to said sleeve, and separate connections for imparting respectively to said sleeve its endwise movements and to said looper-carrier its rocking movements. 30

In testimony whereof, I have signed my name to this specification.

ANDREW B. CLAYTON.
